DOMESTIC CLOTHES WASHING MACHINE
AND DRIER

Fred B. O'Brien, Utica, N. Y.

Application August 3, 1933, Serial No. 683,498

5 Claims. (Cl. 68—37)

My present invention relates to a domestic clothes-washing machine, meaning thereby a machine for not only washing but rinsing and drying the clothes primarily by centrifugal action.

The purpose of this invention is to provide a complete domestic clothes-washing machine of the character described which is of new and improved form and so constructed as to be economical and durable in construction, convenient and durable in operation and generally of such form as to clean, rinse and dry the clothes very efficiently and quickly.

Further purposes are to provide a device of the sort mentioned where the rotated basket used to rinse and dry the clothes is of such construction and combination with the rest of the machine that the lower half of the tub of the machine is left free and clear of all obstructions either fixed or movable heretofore commonly thought necessary to physically move or handle the clothes or to rotate the rinsing and drying basket; to provide a washing machine where the washing operation proper is carried out by forcing a stream or streams of the washing suds or washing solution through and preferably upwardly through the mass of clothes placed in the washing compartment and to have these streams of washing solution of such force, character and location as to be forced repeatedly through the fabric of the clothes and to move the clothes about in the washing compartment so that their position may be frequently changed therein, but is so changed without the application of any physical moving by contacting the clothes except the said stream or streams of washing solution being forced repeatedly through the fabric of the clothes.

A further purpose of my invention is to provide a rinsing and drying basket of such form and so mounted and so connected to the tub and so rotatably moved in a horizontal plane at the top of the tub as not to require any shafts, mounting or other mechanism in the bottom of the tub or projecting up within the tub and in other words to have said basket in the form of a ring with its outer upper periphery suitably mounted upon the top of the tub and driven from one side of the top of the tub whereby the tub below said basket and its closely adjacent partition is left entirely clear for the hydraulic washing operation of the clothes in the bottom of the tub.

Still further purposes are to provide mechanism of the different types mentioned of such construction, form, combination and co-opera-

tion as will effectively help in producing a complete washing machine of the general form suggested.

Another purpose is to provide a washing machine of the type described wherein the hydraulic washing of the clothes may be carried on in the washing compartment simultaneously with the operation of the centrifugal rinsing and drying basket in the upper part of the machine.

Fig. 1 is a vertical central sectional view of a complete domestic washing machine showing one embodiment of my invention.

Fig. 2 is a top view thereof but with the cover removed.

Fig. 3 is a horizontal sectional view mostly on the two levels indicated by the section line 3—3 of Fig. 1.

Fig. 4 is a detail on a somewhat enlarged scale of the parts sectioned as shown in Fig. 1 and of the tub, the outer upper portion of the drier basket, the drive wheel moving the same and adjacent parts of the device.

Fig. 5 is a top plan view of a modified form of arrangement and operation of the pumps, the tub supporting ring 20 and the platform 98 being partly broken away thereabove to more plainly show the pumps, the connecting pipes being also omitted to avoid confusion.

Fig. 6 is a vertical sectional view on line 6—6 of Fig. 5 but on an enlarged scale.

Fig. 7 is a view similar to Fig. 4 but showing the use of a roller bearing to mount the rinsing and drier basket.

Referring to the drawings in a more particular description it will be seen that this machine comprises a tub generally designated by the numeral 8 and providing therein a lower compartment or washing compartment 10 and an upper or drying compartment 9 with said compartments divided by a ring-like partition 12 extending from the side of the tub about half way down and then projecting inwardly and then upwardly as particularly appears in Fig. 1 and terminating at its upper edge in a large aperture or hand hole 14. Through this hand hole 14 the clothes are originally passed down into the washing compartment 10 and when required are brought up again therethrough and deposited in the annular-shaped drier basket 11. This annular basket 11 is roughly U-shaped or channel shaped in cross section through any part of the circle thereof when seen in vertical radial section and is slightly smaller than the corresponding U-shaped part of the drying compartment 9 which is formed by the upper part of the tub, namely the upper

side wall 16 thereof and the annular partition 12 already mentioned.

Conveniently as suggested in Fig. 1 the remainder of the tub forming the washing compartment 5 10 may be originally formed separate from the upper side wall 16 already mentioned; that is, the lower part of the tub will have its side walls 15 begin at the bottom of the side wall 16 of the washing compartment and extend down- 10 wardly gradually sloping inwardly to form the bottom 17 of the tub. The generally centrally sloping bottom 17, however, is transformed about two-thirds the way to the vertical axis of the tub into the sump or drainage compartment 18 15 having side walls 18^a and a bottom 18^b, which sump is normally covered by a removable strainer 60. Securely fastened to the sides of the tub 8 in spaced relation there are provided strong up- 20 standing legs 19 preferably three in number. To 20 these legs there is securely fastened a tub-sup- 25 porting frame 20. This frame is preferably and conveniently in the form of a large strong ring upon which the bottom of the tub rests just inside the legs 19. Adjacent the legs the said 25 frame may conveniently have outwardly project- 30 ing lugs or brackets 20^a securely attached to the legs as by enclosing said legs and being perma- 35 nently secured thereto. Preferably also each leg is secured to the tub by two U-shaped brackets 75.

30 A round cover 21 is provided large enough to cover the entire size of the tub at its top and conveniently fitting onto the top of the tub as by the said cover being provided with a down- 35 wardly projecting flange 21^a fitting the adjacent upper edge of the tub.

The combined rinsing and drying basket 11, herein for brevity called the drying basket 11, is provided with numerous perforations 76 ex- 40 tending through the bottom and both the inner and outer parts of the drying basket almost up to the level of the top of the partition 12. These 45 perforations allow the washing suds or washing solution to drain out from the clothes as they are being placed in the drying basket and so 50 allows the said washing solution to gather in the bottom of the drying compartment 9 from a low spot in the bottom of which a drain pipe 66 conducts the liquid out through the side of the tub and downwardly through a pipe 74 connected thereto extending down to the service pump hereinafter mentioned.

As soon as a desired amount of clothes have been brought up through the hand holes 13 and 14 and distributed as evenly as possible through 55 the ring-like drying basket 11 the said basket will be rotated in the drier compartment 9 by the mechanism and means now to be described.

As appears more particularly in Fig. 1 and on a larger scale in Fig. 4, the metal forming the 60 upper outer wall of the drying basket 11 projects slightly inwardly as at 11^a to form a spatter- 65 guard and safety guard and then projects horizontally outward as at 11^b and is then turned downwardly forming the vertical flange 26. In 70 the angle within this flange 26 and below the horizontal portion 11^b there is located the upper ball race 22 of a large ball bearing consisting of said upper race 22, a plurality of balls 24 and the lower race 23. This lower race 23 is held within 75 the three opposing sides of a large bracket 25 which in the main is annular in shape and has its lower leg extending down along the inner surface of the tub below the level of the said lower race 23 and with said leg of the bracket 75 permanently secured to said portion of the tub,

being the side wall 16 of the drying compartment. It will now be seen that the overhanging upper extremity of the outer wall of the drying basket is hangingly and rotatably supported through the parts of said ball bearing upon the upper part of the tub, namely the upper part of the drying compartment 16. It will also be noted that through the large and substantially braced ball bearings the said basket can be rapidly rotated so as to expel water from the clothes in the said drying basket in an obvious manner by centrifugal action. Also it will be seen that due to the construction and arrangement of said ball bearing and the adjacent part of the tub and basket the said basket can be rotated as fast as required with a minimum of power and noise.

The means for so rotating the drying basket 11 includes a horizontally-arranged driving wheel 27 preferably having a friction face 27^a bearing 20 against the outer face of the flange 26 of said basket. This driving wheel 27 is mounted mostly outside of the tub of the machine near its upper edge conveniently as by having the said wheel project at one point slightly into the space within the tub to engage the said flange 26 as by means of a slot or aperture 80 provided in the side wall 16 of the drying compartment just below the top edge thereof. This driving wheel 27 is securely fastened to the upper end of vertical shaft 28 mounted in upper bearing 34 projecting outward from a strong vertical standard or bracket 39 extending up along the side of the full height of the tub at this point and securely fastened at its lower end to the tub-sup- 30 porting frame 20. Spaced down from the upper bearing 34 there is provided on this bracket 39 a middle bearing 35 and at the lower end of the bracket is provided another outwardly extending bearing 36. In these two bearings are vertically 40 supported the bevel gear shaft 29. For detachably connecting the aligned shafts 28 and 29 there is provided the clutch 30 consisting of clutch member 31 secured to the upper shaft 28 and lower clutch member 32 connected to the lower or bevel gear shaft 29 with the operation of said clutch controlled by the handle 33. Shafts 28 and 29 are held from downward movement by ring 83 secured to shaft 29 and engaging the upper end of lower bearing 36.

Preferably over the top of the drive wheel 27 and around its oppositely extending periphery and therebelow around the bearings 34, 35 and 36 and the shaft 29 is a generally semi-circular shield 37.

At the lower end of the said vertical shaft 29 there is secured the bevel spur gear 40 meshing with a vertically-arranged ring gear 41 on the outer end of shaft 43 extending from the motor 42. This motor is secured to the lower side of a straight mechanism-carrying plate 52 which in turn is suitably rigidly secured to the bottom of the annular frame 20 called the tub-supporting frame and which frame 20 as already described is rigidly secured to the three legs of the machine.

The gears 40 and 41 are suitably enclosed within a grease-filled housing 38. Suitably hung in alignment with the motor 42 from the said supporting plate 52 there are provided in order the service pump 44 and after an intervening clutch 45 three further centrifugal pumps 49, 50 and 51. It will now be seen that the centrifugal service pump 44 is operated all of the time that the motor 42 is running, but that the other pumps 70 75

49, 50 and 51 may be shut off or run as desired by suitable operation of the clutch 45. The clutch 45 consists of a driving member 46 on the shaft of the constantly running service pump 44, 5 a driven member 47 and a control handle 48.

The pipe 74 already mentioned as coming from the drain of the drying compartment 9 extends down outside the tube to the inlet orifice of the service pump 44. The outlet of said pump is connected to the service discharge pipe 81 which extends below the tub and is then provided with a flexible hose 62 long enough to extend up along side the tub as shown in Fig. 1 and have its upper end directed down to the hand holes 13 and 14 10 if the water being moved by the service pump is to be returned to the washing compartment of the machine. If desired, the upper end of this hose may be directed into a house drain or other outlet for the water being directed by the service 15 pump. After the washing solution has been extracted from a batch of clothes the operator causes clean rinse water from any proper source to be placed and held in the rinsing and drying compartment while the clothes are being rinsed in the body of water thus flooding the basket. If 20 it is desired to circulate the rinse water, that can be done by allowing the rinse water to go down through pipe 74 to the service pump which propels it upward through hose 62 which for this 25 operation has its upper end directed down into the basket in the rinsing and drying compartment. When the rinsing has been completed the hose is directed into the house drain or other disposal place and the service pump 30 carries off first the free water and then during the drying operation the remaining water as it is extracted from the clothes by the whirling of the basket. Ordinarily this rinsing operation is 35 repeated once with a new supply of rinse water. From a drain outlet 64 located in the lowest 40 part of the bottom of the sump 18 a pipe 73 extends beneath the sump to a valve 56 and then on into the pipe 74 going into the inlet end of the service pump. Normally the valve 56 is closed 45 so that the service pump does not draw the washing solution from the sump 18 but can do so when the washing compartment is to be finally emptied. From three outlets 63 preferably equally spaced about the vertical wall of the sump 18 nearly to the bottom thereof there extend pipes 70, 71 50 and 72 extending respectively to the inlet openings of the fourth pump 51, the third pump 50 and the second pump 49. From the outlet opening of the pump 49 the pipe 69 extends carrying 55 the water under the power of this pump to a nozzle 58 located in the bottom 17 of the washing compartment. Preferably this nozzle is so constructed as to be flush with the inside surface of the tub, that is, to leave no projecting parts 60 inside the tub, but with the nozzle arranged at such an angle as to direct the water upwardly and inwardly about to a point at the axial center of the wash tub a little below the usual water level 82. Similarly from the second pump 50 65 an outlet pipe 68 takes the water under the power of this pump to a similar nozzle 58 preferably located as this machine is illustrated about a third of the way around the bottom of the washing chamber and about half way between the 70 side wall of the washing chamber and the adjacent or nearest part of the sump. Similarly from the outlet of the third pump 51 a pipe 67 extends to a similar and successively spaced nozzle 57.

75 Figs. 5 and 6 illustrate a modified form of the

means for assembling, mounting and driving the centrifugal pumps. In this construction the motor 90 is hung beneath the tub-supporting annular frame 20 and at the nearest end of this motor shaft 91 is provided the beveled ring gear 41 engaging the bevel spur gear 40 at the bottom of the main vertical shaft 29. The farther end of the shaft 91 of this modification is supported in a suitable bearing 92 depending from the said frame 20. Upon the shaft 91 are provided four 10 separate spaced friction faced drive wheels 93, 94, 95 and 96 counting from the motor 90. The service pump 97 has its casing suitably hung from a strong flat platform 98 which in turn is supported at its opposite ends from the said frame 20. 15

The shaft of the service pump 97 is provided with a friction faced driven wheel 99 constantly engaged with the drive wheel 93 nearest the motor so that this service pump is running constantly whenever the motor is operated. The inlet and 20 outlet openings of this service pump are connected respectively to the inlet and outlet pipes 74 and service discharge pipe 81 as in the previously described form of this invention and consequently operating in the same way and therefore needing no further description at this time. 25

Beneath the platform 98 to the left of the first pump as the parts are illustrated in Fig. 5, there is provided a movable platform 100 hinged at its left hand edge as the parts are seen in 30 Fig. 6 to the platform 98. To the lower face of this movable platform 100 there is secured the casing of the second, third and fourth centrifugal pumps 101, 102 and 103 substantially in alignment and each provided with its own friction 35 driven wheel with the driven wheel 104 of the second pump in line with the friction drive wheel 94 and with the wheel 105 of the third pump in alignment with the friction drive wheel 95 and with the wheel 106 of the fourth pump 103 in 40 alignment with the drive wheel 96. The parts are so fixed that the slight movement of the movable platform 100 moves all of the pumps 101, 102 and 103 and their respective driven 45 wheels sufficiently to bring the co-operating friction wheels of the pumps into engagement with the driving wheels on shaft 91 or out of engagement therewith. As the parts are shown in the enlarged vertical sectional view, Fig. 6, the said movable mounted pumps are being driven when 50 the movable platform 100 is raised and the said pumps will be disengaged and so not running when said movable platform 100 is lowered. The movement of said platform 100 is effected by a part or projection 107 of said movable platform having 55 its lower face engaged preferably by a pair of spaced cams 108 mounted on cam shaft 109. This cam shaft is mounted in bearing brackets 110 depending from the right hand edge of the fixed platform 98 as the parts are seen in Fig. 6. The 60 movement of said rock shaft and consequently of the one or more cams 108 is effected by a control handle 111 secured to and projecting out from the said shaft to a convenient position for manipulation by the hand or foot of the operator. It 65 will now be seen that from the raised operating position of the bodily movable pumps 101, 102 and 103 on movable platform 100, the said pumps with their respective driven wheels may be readily lowered sufficiently to disengage their driven 70 wheels from their respective driving friction wheels by raising the free end of control handle 111. These three bodily movable pumps have their inlet openings connected to the three inlet pipes coming from the sump and have their 75

three outlet openings connected to the discharge pipes carrying the water to the respective nozzles in the bottom of the washing compartment all as hereinbefore described with respect to the 5 first form of my machine. It will be understood, however, that between each pump and the near ends of its pipes there will need to be inserted a suitable length of flexible hose 112 which will allow for the slight swinging of the said 10 pumps without disarranging or having to move the near ends of the inlet and outlet pipes thus connected by said hose to the respective pumps.

It may be stated that in this form of my invention as well as in the first described form of pump 15 driving mechanism of my invention I prefer to have a plurality of separate pumps to force the water to the respective nozzles below the washing compartment. The reason for this is that by employing separate pumps a definite force of water 20 will always be directed out from each nozzle and thereby operate to prevent any nozzle from becoming clogged or obstructed by a heavy mass of clothes happening to become located thereover. When each nozzle has its own pump the 25 power of that pump will ultimately move such obstructing mass of clothes from that nozzle. This might not be the case were one large pump used with the stream of water diverted through separate pipes. It will be understood, however, that 30 the use of one pump or at least of less pumps than the number of water-directing nozzles to be used is within the contemplation of my invention and within the scope of certain of the claims hereinafter set forth.

35 Fig. 7 is in the main similar to Fig. 4 but shows a modified form of construction employing an anti-friction bearing of the roller bearing type to suspendingly mount the upper outer edge of the rinser and drier basket upon the top edge of 40 the tub. The upper outer part of the basket shaped to provide a flange as already described in detail encloses the upper race 84 and the annular bracket 25 on the inner upper part of the tub houses the lower race 85. Between these races 45 are located suitable rollers 86 longitudinally pierced by pins 87 whereby cage or link members 88 are connected for helping to hold the rollers in place and properly spaced. Preferably whichever type of bearing is used to hang the drier 50 basket on the tub, the basket is readily disconnected from its part of the bearing. This may conveniently be accomplished by having removable thumb screws 89 extend down through the upper part 11^b of the basket into holes in the upper race 22 of Fig. 4 or the upper race 84 of the 55 construction shown in Fig. 7. It will be understood however that in ordinary use or even for cleaning the machine after use it will not be necessary to so disconnect the basket from its bearing nor remove the basket from the machine as the basket and upper part of the tub can be properly cleaned by directing a stream of water thereagainst. This removability however may be utilized for occasional thorough cleaning or for possible 60 repairs or replacements.

It is believed that the general operation of the machine is apparent from the description of the machine without following through the different operations in detail. Attention however is called 70 to the fact that not only can the washing operation be carried on in the lower compartment of the tub and the rinsing and drying operation be carried on separately in the upper part of the tub but also that these two operations may be 75 carried on simultaneously without in any wise

interrupting each other or rendering the operation or watching of the machine more difficult. This is an especially advantageous arrangement as it allows the housewife to begin washing a second batch of clothes in the hydraulic washing compartment as soon as she has placed the last of the clothes in the rinsing and drying basket. It will be obvious that the carrying on of these two separate operations simultaneously results in greatly reducing the time necessary to complete 10 the washing and drying operations required for several batches of clothes.

Attention is further called to the fact that the rinsing and drying mechanism and the washing mechanism proper are particularly adapted to cooperate with each other and not to interfere with each other. For instance the mounting of the rinsing and drying basket by its upper outer edge upon the upper edge of the tub instead of mounting the center of the basket upon an 15 upstanding shaft or post projecting up from the bottom of the washing compartment as commonly done heretofore with centrifugally operating drying baskets, leaves the whole area of the washing compartment free and clear of any obstruction. This utilizing of the whole clear area of the 20 washing compartment allows more clothes to be washed in a given sized tub and allows the clothes to be moved about much more freely in the large washing compartment than has heretofore been 25 practicable and aids in the clothes being so constantly moved about by the several streams of water projected upwardly and slantingly thereagainst. It will be seen also that a relatively large 30 area, namely the whole area of the perforated screen 60 is used to draw water from the washing compartment to the several pumps used to circulate the washing solution so that at no place are the clothes sucked down against the screen so 35 strongly as to hold any particular article of the clothes more than temporarily over the strainer. On the other hand the several streams of water sent up by the several pumps tend to lift the clothes upwardly and towards the center of the 40 washing compartment from which they are 45 floated outwardly and then pass downwardly towards the nozzles of the pipes constantly directing the washing solution into the washing compartment. In this way the clothes are constantly 50 tumbled in various directions and pushed apart and new surfaces or parts of the clothes exposed to the different streams of washing solution.

On the other hand the mounting of the rinsing and drying basket by suspending its upper outer edge upon the upper edge of the tub forms a 55 strong well-braced nonvibrating bearing system and suspendingly hanging the basket so that it can be rotated noiselessly and without undue wear upon any of the parts. Suspending the basket by its outer upper edge upon the upper edge of the wash tub also admits of the use of a 60 large annular basket of much greater area than has heretofore been found available as far as I have been informed in any domestic washing machine using the centrifugal type of dryer basket. This large diameter of the basket of course 65 produces a corresponding increase in the periphery or circumference of the basket and so a proper peripheral speed of the basket can be obtained for the needed centrifugal action without having to rotate the basket as fast as is necessary where a smaller basket has to be used. This reduction in speed of the basket operates to obtain quiet- 70 75 80 85 90 95

ness and steadiness in operation and to reduce vibration and wear.

What I claim as new and desire to secure by Letters Patent is:

5. 1. In a domestic clothes-washing machine drier mechanism, the combination of a tub having a circular upper edge, an annular channel partition with its open side upward and extending inwardly from the tub and forming a drying compartment in the upper part of the tub with a central aperture giving access to the space forming a washing compartment in the tub below said partition, an annular, perforated drier basket located in said drier compartment and 10 revolvably mounted at its outer side upon the upper edge of said tub and means engaging the outer side of the basket for rapidly rotating said basket.

2. In a domestic clothes-washing machine drier mechanism, the combination of a tub, an annular channel compartment with its open side upward and forming a drying compartment in the upper part of the tub with a central aperture giving access to the space forming a washing compartment in the tub below said partition, an annular, perforated drier basket located in said drier compartment and revolvably mounted at its outer side upon the upper edge of said tub, a drive wheel mounted outside said tub and enclosing the outer side of the basket for rapidly rotating said basket, a motor near the lower part of the tub and means entirely outside said tub and operatively connecting said motor and said drive wheel.

3. In a domestic clothes-washing machine, the combination of a tub having a circular upper edge, an annular channel partition enclosing a central opening and having its open side upward and dividing the tub into an upper annular, rinsing and drying compartment and a lower washing compartment to which washing compartment access is had through the aperture in the said partition, an annular, perforated drier basket located in said drier compartment and 40 revolvably mounted at its outer side upon the upper edge of the tub, a motor outside said tub near its lower part, means outside of the tub operatively connecting the motor to the outer part of said basket for rotating the basket, a pump driven by said motor and connected at its inlet to the lower part of the washing compartment and connected at its outlet to the lower

part of the washing compartment whereby the washing solution is repeatedly circulated through the washing compartment and is directed in a strong stream against the clothes therein.

4. In a domestic clothes-washing machine, the combination of a tub having an annular channel partition enclosing a central opening and having its open side upward and extending inwardly therefrom and dividing the tub into an upper annular, rinsing and drying compartment and a lower washing compartment to which washing compartment access is had through the aperture in the said partition, an annular, perforated drier basket located in said drier compartment and revolvably mounted at its outer 10 side upon the upper edge of the tub, a motor outside said tub near its lower part, means outside of the tub operatively connecting the motor to the outer part of said basket, for rotating the basket, a pump driven by said motor and connected at its inlet to the lower part of the washing compartment and connected at its outlet to the lower part of the washing compartment whereby the washing solution is repeatedly circulated through the washing compartment and 15 is directed in a strong stream against the clothes therein.

5. In a domestic clothes-washing machine, the combination of a tub having a circular upper edge, an annular channel partition enclosing 20 a central opening and having its open side upward and dividing the tub into an upper annular, rinsing and drying compartment and a lower washing compartment the latter comprising the whole, unobstructed cross area of the tub and to 25 which compartment access is had through the central aperture in said partition, an annular, perforated drier basket located in said drier compartment and revolvably mounted at its outer side upon the upper edge of the tub, a motor 30 outside said tub near its lower part, means outside of the tub operatively connecting the motor to the outer part of said basket for rotating the basket, a pump driven by said motor and connected at its inlet to the lower part of the washing compartment and connected at its outlet to the lower part of the washing compartment whereby the washing solution is repeatedly circulated through the washing compartment and 35 is directed in a strong stream against the clothes 40 therein.

FRED B. O'BRIEN.
